Primary Examiner — Lilyana Bekic(57) **CLAIM**

The ornamental design for a valve cover, as shown and described.

DESCRIPTION

U.S. App. Ser. No. 29/577,873 filed on Sep. 16, 2016, entitled "Valve Cover," is incorporated herein by reference in its entirety.

FIG. 1 is a right top perspective view of a valve cover in accordance with our new design;

FIG. 2 is a top plan view thereof;

FIG. 3 is a front elevation view thereof;

FIG. 4 is a rear elevation view thereof;

FIG. 5 is a left side elevation view thereof, the right side elevation view is a mirror image thereof;

FIG. 6 is a bottom plan view thereof;

FIG. 7 is a left bottom perspective view thereof;

FIG. 8 is a right top perspective view thereof and shown attached to a base; and,

FIG. 9 is a right top perspective view of FIG. 8 and shown attached to a respirator.

The diagonal surface shading lines indicate that the surface of the valve cover is transparent as further described herein. The claimed surfaces of the valve cover are transparent surfaces through which objects on the other side of such transparent surfaces are distinctly seen.

The broken lines showing the base in FIGS. 8-9 and the respirator in FIG. 9 depict environment and form no part of the claimed design. All other broken lines depict portions of the valve cover that form no part of the claimed design.
